UNITED STATES PATENT OFFICE.

HERMAN F. NEHR, OF BROOKLYN, NEW YORK, ASSIGNOR TO BENZIGER BROS., OF NEW YORK, N. Y.

COUNTERBALANCE FOR LAMPS OR CHANDELIERS.

SPECIFICATION forming part of Letters Patent No. 729,886, dated June 2, 1903.

Application filed March 3, 1902. Serial No. 96,387. (No model.)

To all whom it may concern:

Be it known that I, HERMAN F. NEHR, a citizen of the United States, and a resident of Brooklyn, in the county of Kings and State of New York, have invented new and useful Improvements in Counterbalances for Lamps, Chandeliers, &c., of which the following is a specification.

My invention relates to a counterbalance for lamps, chandeliers, &c.; and it has for an object to provide a construction which will operate with little friction and which is simple in construction and not apt to get out of order; also, to provide a construction in which a cable instead of a chain may be used for the flexible suspending connection between the lamp or chandelier and the weight and also one in which the flexible connection cannot become twisted or misplaced on the pulleys, the counterbalance being thereby especially adapted for the safe suspension of very heavy weights. These and other objects of the invention will more fully appear from the following description.

My invention consists in the novel parts, improvements, and combinations herein shown and described.

The accompanying drawings, which are referred to herein and form part hereof, illustrate one embodiment of my invention and serve, in connection with the description herein, to explain the principles of the invention and the best mode contemplated by me of carrying those principles into effect.

Of the drawings, Figure 1 is a side elevation, partly in section, illustrating a counterbalance constructed in accordance with my invention. Fig. 2 is a vertical central section of part of the device, the section being taken at right angles to that in Fig. 1. Fig. 3 is an inverted plan of a detail of the construction.

Like reference-numerals refer to like parts wherever they appear in the drawings.

A counterbalance constructed in accordance with my invention comprises a pair of suspension-pulleys mounted on horizontal axes, a weight having a pair of guide-openings, a flexible member connected by a free loop at the central portion to the weight and extending over the pulleys in opposite directions, then back through the guide-openings

to the lamp-support, where the free ends are secured. The pulleys are preferably arranged side by side on the same axis, and they are preferably made of ample diameter to permit the safe use of a wire cable of such dimensions as to carry the weight with a large factor of safety. The weight preferably consists of a hollow casing, which may be filled with a subdivided ballast material, so that the lamp or chandelier to be suspended may be balanced with nicety.

Referring to the drawings in detail, numerals 1 and 2 represent a pair of supporting pulleys, the same being preferably, as shown, mounted upon the same pivotal pin or shaft 3, which is secured in the lower ends of a suspension-yoke 4 in the usual manner.

5 is the weight, which, as shown, is constructed of sheet metal, the same being spun into any desirable ornamental form, the only essential being in this respect that there shall be ample room provided to receive a sufficient quantity of ballast to balance the article which is to be suspended. The weight-casing

5 is provided with a pair of vertical tubular openings or guide-passages 6, which are located at equal distances from the vertical center of the weight-casing and are separated from each other by a distance corresponding to the diameter of the pulleys 1 and 2. The guide-openings are preferably, and as shown, formed of metallic tube-sections, which are expanded into suitable openings in the opposite ends of casing 5. The upper

end of casing 5 is provided with an opening 7, through which the ballast material may be admitted to or discharged from the casing, said opening being formed by an inwardly-flanged lip 8 of the casing. For the purpose of providing a means of attachment for a suitable flexible suspension connection 9 between the weight and the object to be supported a small casting 10 is fitted in the opening 7 of the casing 5, the same preferably having a circular rim 11, which is adapted to engage the under surface of the flange 8. The casting 10 may be given any suitable form adapted to facilitate the attachment thereto of the flexible connection 9.

Preferably, as is shown, the casting 10 is provided with a diametrically-arranged cross-bar

12, which is formed on the lower side of its central portion with a substantially semicircular groove 13, adapted to receive a central bend or loop of the connection 9.

- 5 The flexible connection 9 extends from the casting 10 to the pulleys 1 2, and after passing around them in opposite directions, one strand on each pulley, the two strands pass downwardly through the guide-openings 6 in 10 the weight and are attached at their lower ends to the yoke 14, which may be provided with a hook 15, from which the lamp or chandelier is suspended. The openings in the opposite ends of the yoke 14 should be in line 15 with the opening 6 in the weight and with the groove at the opposite sides of the adjusting-pulleys, so that when the lamp is suspended from the hook 15 the weight may be passed upwardly or downwardly along the 20 vertical strands of the connection 9 without binding upon them. The flexible connection 9 is preferably in the form of a rope or a cable, and where very heavy weights are supported, as in the case of a large chandelier, this connection is preferably made 25 of wire. Other suitable forms of flexible connection—such as chains, fiber ropes, &c.—may be used, if desired. The ends of the flexible connection 9 should be removably secured to the yoke 14, so that when 30 the connection becomes worn it may be easily replaced by a new one. Where a wire rope is used, the form of attachment between its ends and the yoke 14 preferably consists in 35 casting onto each end of the cable a tapered plug 16, said plugs being adapted to engage upwardly-tapered openings in the yoke 14.

By reason of the form of connection between cable 9 and the casting 10, shown and described, the cable is permitted to slip slightly in either direction, so as to permit the yoke 14 to assume a horizontal position or such a position that the point of attachment to the suspended object will be midway between the 45 two vertical strands of the cable. In this way the device is permitted to automatically adjust itself so as to equalize the strain on all parts of the flexible connection and to keep the parts in their proper relative position so as to 50 avoid all binding.

The operation of the device will be readily understood from the previous description. It will be seen that by reason of the construction shown and described it will be impossible for any part of the cable or flexible connection to become so twisted or otherwise deranged as to interfere with the proper and smooth operation of the device.

My invention in its broader aspects is not limited to the precise construction shown nor to the particular construction by which it may be carried into effect, as many changes may be made in the minor details of the construction without departing from the main principles of the invention and without sacrificing its chief advantages.

Having thus described my invention, what I claim, and desire to secure by Letters Patent, is—

1. In a counterbalance for lamps and chandeliers, the combination with a pair of pulleys mounted to rotate in vertical planes, of a weight having a pair of guide-openings arranged in vertical alinement with the opposite sides of said pulleys, and a flexible member 70 connected by a free loop at its central portion to said weight and extending upwardly and in opposite directions over said pulleys, then downwardly through said guide-openings, said connection being secured at its opposite 75 ends to the lamp-support, substantially as described.

2. In a counterbalance for lamps and chandeliers, the combination with a pair of pulleys mounted side by side on the same axis, of a weight having a pair of guide-openings arranged in vertical alinement with the opposite sides of said pulleys, and a wire cable 80 connected by a free loop at its central portion to said weight, and extending upwardly and in 85 opposite directions over said pulleys, then downwardly through said guide-openings, said wire rope being secured at its opposite ends to the lamp-support, substantially as described.

3. In a counterbalance for lamps and chandeliers, the combination with a pair of pulleys mounted side by side on the same axis, of a weight having a pair of guide-openings arranged in vertical alinement with the opposite 90 sides of said pulleys, and a wire cable connected by a free loop at its central portion to said weight, and extending upwardly and in opposite directions over said pulleys, then 95 downwardly through said guide-openings, said wire cable being secured at its opposite ends to the yoke by means of taper plugs removably fitting in tapered openings in the yoke, substantially as described.

In testimony whereof I have signed my name to this specification in the presence of two subscribing witnesses.

HERMAN F. NEHR.
